INTERNAL COMBUSTION ENGINE

Sylvon B. Blenker, Chicago, Ill.

Application April 19, 1940, Serial No. 330,517

3 Claims. (Cl. 123—54)

This invention relates to an internal combustion engine and more particularly to such an engine wherein a pair of cylinders are positioned in parallel relationship with each other and in each of which is disposed a double headed piston capable of reciprocating movement.

The principal object of the invention is the provision of an internal combustion engine wherein parallel positioned double headed reciprocating pistons are connected at their centers by means of suitable connecting rods so as to impart rotary movement to a crank shaft positioned centrally between the two parallel pistons.

A further object of the invention is the provision of an internal combustion engine of an extremely compact design which will produce an even power flow due to the rotary like application of power impulses to the crank shaft thereof.

Specifically, the internal combustion engine disclosed herein has as its principal point of novelty structure making possible the rotary like application of power impulses to the crank shaft thereof due to its unique utilization of crank shaft positioning in relation to the pistons and cylinders thereof.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed without departing from the spirit of the invention.

The invention is illustrated in the accompanying drawing, wherein:

Figure 1 is a side elevation with parts in cross section showing in detail the reciprocating double headed pistons and the crank shaft and connecting rods in connection therewith.

Figure 2 is a cross sectional view taken on lines 2—2 of Figure 1 and shows in detail the crank shaft of the engine in relation to the pistons and cylinders thereof.

By referring to Figure 1 of the drawing it will be seen that the internal combustion engine comprises a motor block 10 which may be formed in two parts, as shown, or in any other manner known to the art. The motor block 10 is provided with a head 11 at each end thereof which heads incorporate intake and exhaust ports 12 and 13 which are controlled by valves 12A and 13A. The block 10 is so formed as to provide a pair of parallel positioned cylinders 14 surrounded by suitable water jackets 15. Slidably

positioned in each of the cylinders 14 there is a double headed piston 16 each of which is provided with a plurality of suitable rings adjacent each of the head portions thereof so that combustion taking place in the cylinders 14 adjacent the heads of the pistons 16 will serve to impart reciprocating movement thereto.

For purposes of simplicity only the portions of the internal combustion engine incorporating novel structure have been illustrated as the timing and the carburation mechanisms of this internal combustion engine may be essentially the same as that of any double action motor known to the art.

In order that the reciprocating movement of the pistons 16 may be most usefully employed, connecting rods 17 are attached to centrally positioned wrist pins 18 in each of the pistons 16 and to adjacent appropriately shaped sections of a crank shaft 19 which is centrally positioned between the pistons 16 and at right angles thereto. It will thus be seen that reciprocating action of the pistons 16 will continuously impart rotary like power impulses to the crank shaft 19 the net result of which will be a more uniform flow of power to the crank shaft and a more efficient useful action on the part of the internal combustion engine. By referring to Figure 2 of the drawing wherein a fragmentary view is shown, it will be seen that the crank shaft is supported in suitable bearings 20 and that the pistons and cylinders 16 and 14, respectively, while positioned in parallel relation to one another are not positioned in comparable planes which makes possible the application of their power impulses to the crank shaft 19 as shown. Referring again to the drawing it will be obvious that suitable bushings and bearings may be employed in connection with the connecting rods 17 and their connections with the wrist pins 18 in the pistons 16 and the crank shaft 19.

It will thus be seen that an internal combustion engine incorporating a practical mode of operation resulting in a rotary like application of power impulses to a centrally positioned crank shaft has been disclosed some of the various advantages of which are obvious. For example, the normal piston and cylinder wear is greatly reduced in that the pistons are supported uniformly at their respective ends thus preventing any tendency toward wobbling which would result in uneven wear of the cylinder surfaces. Further, the problem of lubrication is simplified as the pistons and cylinders are insured adequate lubrication due to their proximity to the centrally positioned crank shaft and the ease of lubri-

cation thereby made available. It is also obvious that suitable timing and carburation may be readily incorporated which will result in a complete internal combustion engine of considerably greater efficiency than has heretofore been known to the art particularly with respect to the rotary like application of power impulses to the crank shaft portion thereof.

What I claim is:

1. An internal combustion engine characterized by the incorporation of adjacently positioned double headed cylinders on different planes, a double headed piston slidably positioned in each of the said double headed cylinders, wrist pins positioned centrally in each of the said pistons, together with openings in the said pistons adapted to provide for the positioning therethrough of connecting rods, said connecting rods establishing connection with a crank shaft centrally positioned in relation to the said pistons and at right angles thereto so that reciprocating movement of the said pistons results in the rotation of the said crank shaft substantially as described.

2. An internal combustion engine including a pair of spaced parallel cylinders, a piston recip-

rocally mounted in each of the said cylinders, slots in each of the said pistons, the said pistons adapted to receive power impulses at the opposite ends thereof, a crank shaft disposed between the said cylinders at right angles thereto, connecting rods attached to the said cranks of the said crank shaft and to the said pistons and functioning through slots formed therein and secured to the said pistons by wrist pins substantially as described.

3. An internal combustion engine including a cylinder block having a plurality of parallel cylinders spaced apart, a crank shaft journaled in said block between and disposed at right angles to the axis of the said cylinders, cranks formed in the said crank shaft opposite the said cylinders, a piston reciprocally mounted in each of the said cylinders and having longitudinally disposed openings therein providing for the entrance thereinto of a piston rod, said rod secured to the said piston at a central location and to the cranks in a conventional manner, whereby at each movement of the said pistons said connecting rods will move the said cranks of the said crank shaft with a rotary action.

SYLVON B. BLENKER.
